L'ÉLECTRICITÉ, OF SAME PLACE.

MULTIPLE TELEPHONY AND TELEGRAPHY.

SPECIFICATION forming part of Letters Patent No. 628,247, dated July 4, 1899.

Application filed December 30, 1897. Serial No. 664,720. (No model.)

To all whom it may concern:

Be it known that we, MAURICE HUTIN and MAURICE LEBLANC, citizens of the Republic of France, and residents of Paris, France, have invented certain new and useful Improvements in Multiple Telephony and Telegraphy, of which the following is a specification.

Our invention relates to telephony and telegraphy, and comprises a method and apparatus of sending simultaneously over the same line a number of telephonic or telegraphic messages, or both.

Our invention also comprises a new current-reinforcer by which we are enabled to overcome and neutralize the resistance of a long line both in telegraphy and telephony and various other improvements to be hereinafter more specifically described and claimed.

In the drawings attached to this specification, Figure 1 is a general view of our improved system of telephony in a simple form. Fig. 2 is an elevation of the commutator or distributor and motor. Fig. 3 is an end view of the motor. Fig. 4 is a diagram of our improved system of telephony arranged in such a way that the telephonic currents, the synchronizing-currents, and the calling-currents may be simultaneously transmitted over the same set of line-wires. Fig. 5 is a diagram of our system of multiplex telegraphy. Fig. 6 is a diagram of the preferred form of distributor, with connections, as applied to a system of telegraphy or telephony. Fig. 7 is a view of our improved current-reinforcer applied to a system of telephony. Fig. 8 is a view of another form of the same. Fig. 9 is a view of one terminal station of a complete system arranged for transmitting simultaneously six telephone-messages, six telegraph-messages, and synchronizing-currents over a single pair of line-wires.

The arms 1' 1', Fig. 1, mounted on the shafts 2' 2', (best shown in Fig. 4,) are supposed to be maintained in synchronous rotation by the motors 3' 3'. Each of these arms rotates about a six-part commutator or distributor 4' 4' and serves to place the various segments of the distributor successively in connection with

the line-wire 5 5. From each of the segments 5 of each of the distributors 4' is carried a connection to a plug-terminal 6 6', while other plug-terminals 7 7' are connected to the ground-wires 8 8'. These ground-wires are connected to earth-plates 9 9', (shown in dotted lines,) but may, if preferred, be joined by the return-wire 10 10. The two distributors are supposed to be located at different telephone central stations, in which case the plug-terminals 6 7 6' 7' may be connected to contacts on the switchboard of the station. We have shown at one pair of terminals at each station a pair of wires 11 12 11' 12', leading to the subscribers' stations, (indicated diagrammatically at 13 13' as comprising each a telephone-receiver 14 14', an induction-coil 15 15', and a battery 16 16', with a microphone-transmitter 17 17' in the local primary circuit of the induction-coil.) The motors 3' 3' may be constructed like ordinary rotary transformers and comprise each a field-magnet structure wound with coils 18 18' and an armature 19 19'. The armatures of these machines are wound like those of ordinary direct-current motors and connected, respectively, to commutators 20 20', on which bear brushes 21 22 21' 22', supplied with current from the direct-current generators 23 23'. The field-magnet coils 18 18' are preferably excited in multiple with the armatures. Rheostats 24 24' are interposed in series with the direct-current sources 23 23', respectively. It will be seen that by the adjustment of these rheostats it is possible to maintain the two motors in approximately synchronous rotation. In order to render this rotation rigidly synchronous, we place on the shafts of the motors rings 25 26 25' 26', connected to diametrically opposite segments of the commutator, upon which rings bear the brushes 27 28 27' 28', respectively. These latter brushes at one station are connected to the brushes at the other station through the line-wires 29 30. For the circuit thus established the motors 3' 3' act as generators of alternating currents operating to synchronize the rotation of the two motors. If one of the motors tends to run in advance of the other,

it will generate and furnish current to the other motor, tending to speed it up, while its own speed is thereby reduced. The alternating currents thus passing over the line 29 5 30 we call "synchronizing-currents." It will be obvious that the wire 30 may be omitted and an earth connection substituted, as indicated in dotted lines. The condenser 31 serves to neutralize the self-induction of the circuit 10 connected to the brushes 27 28 27' 28'. It will be seen that by such a system the various subscribers' stations 13 13', &c., connected between the contacts 6 7 6' 7', &c., will be successively connected together by the arms 15 1 1', two at a time, for very brief intervals of time.

We have verified experimentally with reference to such a system, first, that this intermittent connection does not prevent the transmission of vocal sounds when the interval of time between the successive contacts of the arms 1 1' with any particular segment of the distributors 4 4' is not greater than about one one-hundredth of a second; second, that the 20 passage of the brushes carried by the arms 1 1' from one segment to the other does not produce any parasitic sound in the telephone-receivers; third, that the intensity of the sounds transmitted diminishes very slightly with an 25 increase in the number of stations simultaneously served and that with commercial telephonic apparatus placed in operative relation with a system thus constituted it is possible to exchange with the greatest facility at least five simultaneous conversations.

We have thus established the principle of a system of multiplex telephony which renders possible the utilization of existing line-wires, switchboards, and other apparatus.

Figs. 2 and 3 show the practical construction of the commutators and motors. In these figures 3 is the motor, having its field-magnets excited by magnetizing-coils 18. The armature 19 is provided with a commutator 20, 45 on which bear brushes 21 22, and with rings 25 26, on which bear brushes 27 28. In order to assist in rendering the motors rigidly synchronous, we place on the field-magnets, preferably at the polar extensions, a flux-screen 50 32, such as is described in our Patent No. 529,272, dated November 13, 1894. As explained in the said patent, this flux-screen tends greatly to assist the maintenance of synchronism and to prevent violent oscillations 55 or variations of speed. This motor drives the distributor 4, on which bears the brush 1, corresponding to the arm 1 in Fig. 1. Each segment of the distributor is connected to a ring 33 33, on which rings bear brushes 34 34, 60 connected to the plug-terminals 6 6. (Shown in Fig. 1.) The shaft of the motor is supported on suitable bearings 35 35.

We find it preferable in practice to utilize the same line-wires which transmit the telephonic currents to also carry the synchronizing-currents, which result we accomplish by the improved system shown in Fig. 4. In this

figure of the drawings 4 4' are the distributors, driven through the shafts 2 2' by the motors 3 3', as before. These motors are supplied with currents from the direct-current sources 23 23', here shown as storage batteries, and the regulating-rheostats 24 24'. 36 36' 37 37' are the line-wires, extending from one station to the other and connected at 75 their ends, as shown, to each other and to the wires 38 38', so as to form a complete metallic circuit grounded at each end through the earth-plates 9 9'. It is evident that a pair of 80 line-wires thus connected may be the seat of two sets of currents, one set passing in the closed circuit 36 36' 37' 37 and the other set passing from the earth-plate 9 through the wire 38, through 36 36' 37 37' in multiple, and to earth through the wire 38' and earth-plate 85 9'. We interpose in the conductor 36 36' the primary windings 39 39' and in the conductor 37 37' the other primary windings 40 40' of a pair of transformers and place in like inductive relation to each pair of primaries 39 40 90 39' 40' a single secondary 41 and 41', respectively, each connected at one end to one of the brushes 1 1', bearing on the distributors 4 4', and at the other end of the common returns 8 8', corresponding to the circles 8 8' in 95 Fig. 1. We interpose in each of the six circuits leading from the brushes 34 34 34' 34', bearing on the rings 33 33 33' 33' on the shafts of the distributors, the terminals 6 6' 7' 7, which, as above explained, may be placed on 100 the main switchboard of the station and connected to the apparatus of any desired subscribers. The primaries 39 40 39' 40' are so wound that their effects upon the secondaries 41 41' or the effect of the secondaries 41 41' 105 upon them will be cumulative, so that current passing, for example, in the coil 41 will induce current which will flow by the path 39, 39', 36', 37', 40', 40, 37, and 36 and generate in turn a corresponding current in the secondary 41', and vice versa. On the other hand, any current passing from the earth-plate 9 through the wire 38 will divide at the points 36 37 and will pass through the primaries 39 40 39' 40' in such a way as to produce no effect whatever upon the secondaries 41 41'. This path may therefore be used for calling-current or for synchronizing-currents or for any other purpose whatever. The 110 grounded line-circuit we place in inductive or conductive relation with the circuit including the rings 25 26 25' 26' of the motor-generators 3 3', which furnish the synchronizing-currents, and we are thus able to transmit simultaneously the telephonic and synchronizing currents over a single pair of conductors. In this particular figure of drawings the synchronizing-currents furnished by the motor-generators 3 3' are shown as being inductively transferred to the grounded line-circuit by the transformers 42 42'. We are 115 thus enabled to use synchronizing-currents of high potential on the line, which is of advantage if the line has a high resistance. It 120 125 130 135

will be noticed that any earth-currents tending to flow in the circuit will also be divided, as are the synchronizing-currents, between the primaries 39 40 39' 40' and will not affect the telephonic instrument. We thus obtain all the advantages of a complete metallic circuit as far as the telephonic interconnection is concerned. Another advantage of this arrangement is that it renders it possible to give a very high potential to the synchronizing-current without transmitting that voltage to the telephonic switchboard or to the subscribers' stations. In order that one of the central stations may be able to call the other, we place in the branch circuits 43 43' from the wires 38 38' the bells 44 44' and the calling-generators 45 45', which may be of the Abdank Abdakanowitz type, well known in the art. In order to separate the calling-currents from the synchronizing-currents and to force each to flow in the proper branch, we render the branch circuits from the wires 38 38', leading to the transformers 42 42' and to the bells 44 44', respectively, resonant, each to the frequency of the current which it is designed to carry, by the insertion therein of condensers or condensers and reaction coils, as indicated at 46 47 48, &c. The action of a system thus constituted is as follows: Suppose, for example, that one subscriber, as 13, wishes to communicate with another subscriber, as 13'. The subscriber calls in the usual way the central station to which he is connected and asks to be put in communication with 13'. The operator at this central station then calls the operator at the other central station by means of the calling-generator 45. The current from this generator passes through the bell 44, the resonator 47 48, the wires 43 and 38, and divides, flowing through the wires 36 36' and 37 37' in multiple without affecting the secondary 41' 41', and from 36' 37' passes through the wires 38' and 43', through the resonator 47' 48', and through the bell 44', actuating this bell. From the bell the current returns through the generator 45' and the earth-plates 9' 9 to the generator 45. Having secured the attention of the operator at the second station, the operator at the first station requests that the subscriber 13' be called in the usual way and plugged to whichever pair of terminals 6' 7' may happen to be free at that particular instant. At the same time the operator at the first station connects the subscriber 13 to the corresponding pair of terminals 6 7, as is clearly indicated in the drawings. These two subscribers are now in a condition to communicate with each other without interference from or with other subscribers or with the synchronizing and signaling currents that may at the same time pass on the line. We have thus described a system by which we are enabled to send a number of telephonic messages, proper calling-currents, and all necessary synchronizing-currents simultaneously over the same pair of line conductors.

Although we prefer to maintain the commutators or distributers in synchronous rotation by means of the apparatus above described, since this gives better results than any other method with which we are acquainted, it will be obvious that various other methods may be used with more or less success. Thus, for instance, the distributers at the two stations may be driven independently by clockwork or by synchronous tuning-forks and be corrected at intervals for differences of speed by synchronizing impulses, as is well known in the art; but in that case the synchronizing impulses may by our system be sent over the same line which carries the telephonic and signaling currents simultaneously without disturbance of either by the others. It will also be obvious that we may replace the telephonic apparatus hitherto described by telegraphic apparatus without altering the operation of our invention; but the problem of multiplex telegraphy is in some respects simpler than the problem of multiplex telephony, particularly for the reason that in telegraph-work alternating currents are not necessarily employed. Fig. 5 shows one station of a sextuplex telegraph system arranged in accordance with our invention. In this figure 38 is the line-wire coming in from the distant station and leading to the distributer 49 through the brush 50. The distributer is driven by the motor 3, provided with a commutator 20 and supplied with current from the direct-current source 23 through the resistance 24, as in the systems above described. On the shaft 2 of the distributer 49 are placed a number of rings 51 51, with brushes 52 52, similar to the rings 33 33 and brushes 34 34 in Fig. 4. From these rings wires lead to the telegraph-keys 53 53 and sounders 54 54, and thence through the common return 8 to the telegraph-battery 55 and the earth-plate 9. A branch wire leads from the wire 38 through the condenser 46 and self-induction coil 56, though the self-induction coil may be omitted when the self-induction of the motor is sufficiently great, through the rings 25 26 of the motor-generator 3, and to earth at 9. The motor-generator 3 is in all respects similar to those shown in Figs. 2 and 3 and is supplied with direct current in any desired manner, as explained above. The condenser 46 and self-induction coil 56 form an electric resonator tuned to the frequency of the synchronizing-currents, which will prevent the passage of the telegraphic currents through the motor-generator. In this arrangement we prefer to give to the synchronizing-currents a very high frequency in order that they may be effectively prevented by the self-induction of the telegraphic apparatus from flowing through the branch circuits in which the telegraphic apparatus is placed. Where the transmission-line is very long and particularly where a large number of messages are to be transmitted over the same wire simultaneously, we prefer to replace the sounders 54 54 by sensi-

tive relays, as shown at 57, each acting simply to open and close the key 58 in a local circuit in which is placed a battery 59 and a sounder 60. We omit in this figure the connections to the switchboard, &c., which will be obvious to those skilled in the art from what has been said above in connection with telephone systems.

We have thus far supposed that the number of segments of the commutator or distributor is equal to the number of subscribers to be simultaneously served; but in general, in order to reduce the speed at which it is necessary to drive the distributor, it is preferable to multiply the number of segments, as shown in Fig. 6. In this figure, which represents the application of a multiple-segment distributor to the system shown in Fig. 4, 36 37 are the line-wires, connected at one end to each other and to the ground-wire 38. In these wires are interposed the primaries 39 40, acting jointly on the secondary 41, as fully explained above. One end of the secondary 41 is connected to four brushes 11, bearing at equidistant points on the distributor 4. The various segments of this distributor are numbered 61^a 61^b 61^c 61^d 61^e 61^f 61^g 61^h 61ⁱ, &c. All of the segments numbered 61^a are connected to the ring 33^a, on which bears the brush 34^a, and so on, and the various brushes 34^a 34^b, &c., are connected to plug-contacts 6, leading to the subscribers' stations, while the plug-contacts 7, which form the returns from the subscribers' stations are connected, through the wire 8, to the secondary 41. The operation of this distributor as distinguished from that of the distributor shown in Figs. 1, 3, 4, &c., is simply to render it possible to drive the apparatus at a lower speed and to reduce the resistance introduced by the rubbing contacts and also to reduce the variations of current due to any slight jarring of the brushes. In all other respects its operation is the same as that of the forms above described.

We have stated above that it sometimes becomes advisable to relay the telegraphic currents. When the multiplexing is pushed beyond a certain limit, it also becomes advisable to relay or reinforce the telephonic currents, and we may use for this purpose the new and improved reinforcer forming part of our present invention. Referring to Fig. 7, in which the reinforcer is illustrated in connection with a simplex system of telephony, the line-wire 62 62', grounded at each end through the earth-plates 9 9', connects two telephone-stations, which stations consist, respectively, of the receivers 14 and 14' and the induction-coils 15 and 15', with microphone or other transmitters 17 and 17' and batteries 16 and 16' interposed in the local circuits of the induction-coils, as usual. Our improved relay or current reinforcer (shown at 63) consists of an armature 64 of the direct-current type connected to the commutator 65, on which bear brushes 66. The field-magnet

winding 67 of this reinforcer is connected in series with the brushes and with the line 62 62'. The reinforcer, which obviously consists, as far as described, of an ordinary series-wound dynamo-machine of the direct-current type, is driven by any preferred source of power. The electromotive force developed by such a machine is known to be at all times proportional to the current flowing therethrough, supposing, of course, that the iron is properly laminated and sufficiently free from magnetic hysteresis. Therefore the electromotive force of the reinforcer will be proportional to the current flowing in the line, and the machine will act to strengthen the telephonic current and to increase the loudness of the sound. In order to neutralize the self-induction and the armature reaction of the reinforcer, we prefer to place on the field-magnets an additional neutralizing-winding 68, so designed and wound that the magneto-motive force which it generates is at all times exactly equal and opposite to the magneto-motive force of the armature. We have described and illustrated the preferred mechanical construction of such a machine in our pending application, Serial No. 664,719, filed December 30, 1897. While obviously such a relay or reinforcer may be interposed in each one of the branch circuits shown in our multiplex system in which the telephonic apparatus is placed, it is preferable to use, as shown in Fig. 8, a single machine to reinforce all the currents flowing in the line. In this figure 36 36' 37 37' are the two line-wires of the system shown in Fig. 4, and 39 40 39' 40' are the primary windings leading to the distributors. The reinforcer 63 consists of a series-wound direct-current dynamo-electric machine with two windings on its armature, which windings are connected, respectively, to two commutators 65^a 65^b, on which bear, respectively, the brushes 66^a 66^b 66^c 66^d. One of these commutators and one of the two equal series field-windings 67^a 67^b is interposed in each of the line-wires 36 36' 37 37'. The field-magnet windings are so arranged that the effect of the telephone-currents flowing in the complete metallic circuit 36 36' 37 37' will be cumulative, while currents flowing in at 38 and out at 38' will act differentially in such a way as to produce no effect in the field-magnets. In the same way the armature-windings are so disposed that the electromotive forces created by them will be such as to reinforce the current flowing in the path 36 36' 37 37', but will not tend to cause any current to flow in the external circuit 38 38'. We may, if preferred, add to such a machine neutralizing-windings, such as are indicated in Fig. 7.

As it has been shown that currents flowing in at 38 and out at 38' in the system shown in Fig. 4 will have no effect whatever on the apparatus interposed in the circuits of the distributors 4 4', and as it has also been shown that we are able to separate the high-frequency current necessary for synchronization

from the direct current or low-frequency reversed current necessary for telegraphy, it follows that we are able to use the same pair of line conductors both for multiplex telephony, 5 multiplex telegraphy, and synchronization. One end of a system accomplishing such results is shown in Fig. 9. In this figure the line-wires 36 37, in which are introduced the primaries 39 40, are connected as in the system shown in Fig. 4. From the secondary 41 a wire leads to the brush 1 of the distributor 4, and from the rings 33 33 wires lead to the plug-contacts 6 6. Other plug-contacts 7 7 are connected, through the return-wire 8, to 15 the secondary 41. This is obviously our system of multiplex telephony above described; but, if preferred, we may introduce in any of the subscribers' circuits leading from the contacts 6 7 telephony relays. Such an arrangement is shown connected to the plug-contacts 6^a 7^a. The relay 69 consists of a magnet connected in series with the subscribers' line in operative relation with the diaphragm of a microphone 70. In series with the microphone 25 is placed a battery 71 and a telephone-receiver 72. One coil of an inductorium 15, whose other coil is in a local circuit with the battery 16 and the transmitter 17, is mounted in series with the relay 68; but this relay may obviously be replaced by the current-reinforcer 63, (shown in Fig. 8,) in which case one reinforcer placed in circuit with the wires 36 37 will serve to increase the sound of all the telephonic receivers simultaneously, as described with reference to Fig. 8. From the 35 wire 38, connected to the common point of the conductors 36 37, lead two branch circuits. The first passes through the tuning-condenser 46, through the rings 25 26 on the motor 3, through the self-induction coil 56, and to earth at 9. The branch carries the synchronizing currents and is tuned therefor. The second branch passes to the brush 50 of the distributor 49 and thence, by the 45 rings 51 51 and brushes 52 52, to the telegraphic apparatus 53 53 54 54 57, fully described above in connection with Fig. 5. The battery 55 is interposed in the return-wire 8 for the purpose above set forth.

50 As all the elements of this system have been described above, it is only necessary to here state that each element performs its normal function without affecting or impeding the normal functions of the other elements, it being understood that the self-induction of the 55 telegraphic instruments is made so great as to prevent the passage of the synchronizing currents.

It will be obvious that a common return-wire 60 may be substituted for the earth connections 9 9' in all cases.

We do not limit ourselves to the specific forms herein shown and described, as it is obvious that they may be greatly varied without departing from the spirit and scope of our 65 invention; but

We claim as our invention and desire to secure by Letters Patent—

1. In a system of multiplex telephony or telegraphy the combination with a line-wire, 70 a distributor at each end thereof acting to connect the line intermittently and successively with a number of telegraphic or telephonic instruments, means for driving the distributors, and means for synchronizing the 75 distributors, the said synchronizing means being controlled by current passing from the line at each end to ground, through a selective resonant branch,

2. In a system of multiplex telegraphy a 80 line, a distributor at each end of the line and a means for synchronizing the distributors, in resonant branches of the line, substantially as described.

3. In a combined system of multiplex te- 85 lephony and telegraphy, a complete metallic circuit consisting of conductors connected together and grounded at each end, and afford- 90 ing two current-paths, one through the metallic circuit and one from earth to earth through the metallic circuit-conductors in multiple, a telephone or telegraph distributor at each end of the circuit, the distributors being connected together through one of the paths, and means for synchronizing the dis- 95 tributors by current passing through the other of said paths, substantially as described.

4. In a combined system of multiplex te- 100 lephony and telegraphy, a complete metallic circuit consisting of conductors connected together and grounded at each end, affording 105 two current-paths, one through the metallic circuit and one from earth to earth through the conductors in multiple, a telephone-dis- 110 tributor at each end supplied with current through one of the said paths, a telegraph-distributer at each end, supplied with current through the other of said paths, and means for synchronizing the distributors by 115 current passing through the conductors in such a way as not to affect either the telephonic or telegraphic apparatus.

5. The combination with two wires joined at each end to each other and to the earth or other return, of four primary inductive windings, two in each wire, forming a pair for 120 each end of the metallic circuit, and two sec- 125 ondaries, each in inductive relation to one pair of the inductive windings, a distributor in each secondary, and means for synchronizing the distributors, interposed in the ground or return wire, substantially as de- 130 scribed.

6. The combination with a line composed of two wires joined together at each end and connected to the earth or other return, of four primary inductive windings, two in each wire, forming a pair for each end of the metallic circuit, and two secondaries each in inductive relation to one pair of primaries, a distributor in each secondary, a second distributor in a ground or return connection at each end of

the line, and means for synchronizing the distributers interposed in a ground or return connection.

7. The combination with telephone central stations, of a line connecting the same, a distributer supplied with current from said line at each end, a continuous current motor for driving each distributer, having connections between their armatures, whereby the same may operate as alternating-current generators to synchronize each other, and connections from the distributers to terminals adapted to be connected to subscribers' stations, other similar terminals, and connections from the last-named terminals to a common return.

8. The combination with a system of multiplex telegraphy or telephony, of a pair of distributers, an electric motor of the direct-current type for driving each distributer, independent means for regulating the speed of said motors, and connections whereby the two motors act as two alternating-current dynamo-electric machines in multiple, and tend to synchronize.

9. The combination of line-wires, connected to each other, and to earth, or to a common return, at each end, two transformers each with a plurality of primary windings and a common secondary, the primaries of the transformers being so interposed in the line-circuits that a current flowing from earth to earth will not affect the secondaries, but that an alternating current flowing in one secondary will produce current in the other secondary, and a distributer in each secondary circuit.

10. In a multiplex telephone system, a pair

of entering line-wires, each including one primary coil of a transformer, a secondary coil on the transformer, in cumulative inductive relation to both of the primaries, a distributer in circuit with the secondary coil, and a common ground for both line-wires through a device for controlling the rotation of the distributer, substantially as described.

11. In a multiplex telephone system, a pair of entering line-wires, each including one primary coil of a transformer, a secondary coil on said transformer, in cumulative inductive relation to both of the primaries, a distributer, supplying current to telephonic apparatus, in series with the secondary coil, and a common ground for both wires divided into two selective branches, one including means for synchronizing the distributer, and the other including a calling device, substantially as described.

12. In a system of telephony, in which synchronizing and telephonic currents are carried by the same line conductors simultaneously, the combination of a current-reinforcer on the line, consisting of a series-wound dynamo connected so as to be energized exclusively by the telephonic currents and thereby selectively reinforcing the same, substantially as set forth.

In testimony whereof we have signed our names to this specification in the presence of two subscribing witnesses.

MAURICE HUTIN.

MAURICE LEBLANC.
